UNITED STATES PATENT OFFICE.

FREDERICK L. GOSS AND SAM G. GOSS, OF CHICAGO, ILLINOIS, ASSIGNEES
TO THE GOSS PRINTING PRESS COMPANY, OF SAME PLACE.

DAMPING-MACHINE.

SPECIFICATION forming part of Letters Patent No. 363,326, dated May 17, 1887.

Application filed October 11, 1886. Serial No. 215,024. (No model.)

To all whom it may concern:

Be it known that we, FREDERICK L. Goss and SAM G. Goss, citizens of the United States, residing at Chicago, in the county of Cook and State of Illinois, have invented a certain new and useful Improvement in Damping-Machines; and we hereby declare the following to be a full, clear, and exact description of the same.

10 Our invention relates to a machine for dampening paper preparatory to printing upon it, the leading objects being to provide for the convenient handling of ponderous rolls of paper in the process of dampening and to effect uniform and rapid dampening of the paper.

15 To this end our invention consists in the general construction of a machine for transferring the paper from its initial roll to a second roll, directing against it between the rolls 20 during the transfer a continuous spray of water extending across its entire width, and for discharging the dampened roll; and it further consists in certain details of construction and combinations of parts, all as hereinafter more 25 fully set forth.

30 In the drawings, Figure 1 is a side elevation of our improved machine; Fig. 2, a similar view of a broken portion of the same, partly in section, illustrating by dotted lines the operation of discharging a roll dampened while it was being wound; Fig. 3, a central longitudinal broken section of the device; Fig. 4, a 35 broken sectional view taken on the line 4-4 of Fig. 1, and Fig. 5 a broken sectional view taken on the line 5 of Fig. 1.

A is the frame of the machine, provided with suitable extensions and bearings to support the parts hereinafter described.

40 B is a roll of dry paper. Rolls B, as they come from the paper-mill, are commonly of a uniform or substantially uniform size, and are wound upon hollow metal shafts or spools t. Preparatory to placing a roll, B, in its operative position upon the machine, a shaft, s, of a 45 size and length to fit into the bearings s' on opposite sides of the machine, is passed through the spool t in a manner to extend a distance beyond the spool at each end. To insure the centering of the roll upon the shaft s, movable 50 cone-shaped stops r, Fig. 5, are provided upon

the shaft s, one to enter each end of the spool t, the stops being held in place by set-screws r'. The stops r, it will be seen, perform the double function of centering the roll upon its bearings and preventing its shifting toward either side of the machine. To avoid the necessity of lifting the roll B into its bearings s', an extension, q, is provided on each side of the machine. The upper surfaces of the extensions q incline from the sides of the bearings s' to a point in line with or below the center of the roll B as it lies upon the floor, and form guides for the shaft s, upon which to roll the same until it drops into the bearings s', when the roll B occupies its position upon the machine. 60

Between the roll B and a drum, D, herein-after described, is a coverless water-tight trough or douche-pan, C, supported to extend transversely across the machine, being tilted, 70 as shown, and having an outlet, p. Toward the bottom of the douche-pan, and at the side of the same nearest the roll B, a perforated water-pipe, o, closed at one end, is provided, to extend longitudinally of the douche-pan and 75 through bearings n at each end of the same. The perforations o' in the water-pipe extend along the pipe from one end of the douche-pan to the other, and are arranged to direct parallel streams. 80

The open end of the pipe o is connected to a water-supply by means of a suitable loose coupling of common construction (not shown) in a manner to enable the pipe o to be turned in its bearings to change the direction of the 85 streams, the pipe being fastened in any adjusted position by means of a set-screw, n', in the bearing n. Toward the side of the douche-pan, opposite the pipe o and running parallel with the same, is an adjustable deflector or 90 spattering-board, G, pivoted at each end to the adjacent end of the douche-pan. A stream of water from the perforations in the water-pipe o, directed against the spattering-board G, is deflected to any desired angle by the proper 95 adjustment of the spattering-board, which is held in its adjusted position by the thumb-screw i, and a spray of water of any required density can thus be deflected against the paper which passes across the douche-pan, as here- 100

inafter described. Between the roll B and the douche-pan we provide a guide-roller, j, extending transversely across the machine to rotate in bearings j' on the frame A.

5 Beyond the douche-pan and surrounding the driving-shaft m, to which it is keyed, is the drum or roller D, extending transversely across the machine, the driving-shaft m being suitably journaled upon brackets l on each side of the frame A, and receiving its motion from the driving-pulley k. The purpose of the drum D is to rotate the damp-paper spool E, as hereinafter described.

The spool E has its bearings between guide-arms F F' of the pivotal brackets I, arranged on each side of the machine, and in its normal position the spool rests upon the drum D, the journal ends of the spool extending slightly beyond the outer sides of the arms, for a purpose hereinafter described.

The operation of our machine thus far described is as follows: A roll of dry paper, B, wound upon its spool t, is adjusted upon the shaft s and placed in position upon the machine, all as hereinbefore described, and in a manner to allow the paper to unwind from the under side of the roll, as shown. The loose end of the web upon the roll B is then passed over the roller j, thence over and across the douche-pan C, and under and around the drum D to the spool E, upon which it is fastened, the roller j, douche-pan, and drum being arranged with relation to each other to allow the web of paper to pass across the opening of the douche-pan on an inclined plane parallel (or nearly so) with the bottom of the latter. The water-pipe o is adjusted to cause a stream of water from the perforations o' to strike against the spattering-board and be deflected upward in a spray of the proper density by the adjustment of the spattering-board, as before described, and dampen the web. The machine being set in motion, the friction of the rotating drum D against the web, which passes around it and against the spool E, (first, and after the first revolution of the spool the web upon the same,) causes the paper to unwind from the roll B upon the spool E, to form the dampened roll E'. The increase in circumference of the roll E', as it rests upon the drum D, causes the spool E to rise in its bearings between the arms F F'.

Pivoted to the outer side at the upper end of each arm F is a bracket, H, provided with curved fingers h h', the spaces between the fingers forming sockets h'', to receive the journal ends of the spool E, as hereinafter described. In the normal position of the brackets H (see Fig. 1) the fingers h extend across the openings, while the fingers h' hang vertically downward along the arm F in rear of the opening. In its rise toward the upper ends of the arms F' (which are somewhat shorter than the arms F) the ends of the spool E (projecting beyond the sides of the arms F F', as before described) come into contact with the fingers h and cause

the brackets H to turn, the fingers h' passing upward underneath the ends of the spool over the beveled spring-catches g upon the arms F'. In passing, the fingers h', bearing against the beveled surfaces of the spring-catches g, force them inward, causing the catches to spring out when passed and present shoulders for the fingers h' to rest upon. When the fingers h' have passed the spring-catches g, the roll E' is of a size equal to the capacity of the machine, at which point it is necessary to stop the machinery and discharge the roll, which latter operation is accomplished in the following manner: The brackets I, carrying the arms F F', before described, are keyed upon a shaft f, which is journaled upon the frame A behind the driving-shaft m. The shaft f projects beyond the frame A, (on the side of the machine opposite to the driving-pulley,) and keyed to the shaft f, at its end thus projecting, is a large cog-wheel, J, in mesh with a smaller cog-wheel, K, also keyed to its shaft and journaled upon projections L of the frame A. Keyed to the same shaft and adjacent to the cog-wheel K is the lever M, provided at its upper end with a suitable lateral handle. (Not shown.) To discharge the roll the lever M is turned in the proper direction to cause the cog-wheel K to rotate the cog-wheel J in the opposite direction and with it the brackets I. When the arms F F' reach the position indicated by dotted lines in Fig. 2, the spool E rolls out of the sockets h'', and the roll E' drops upon the floor. To adjust the bracket I again in its normal position, the lever M is turned in the opposite direction until stopped by the contact of the projections I' on the brackets I with the projections L, the latches e, when adjusted, serving to keep the projections I' and L rigidly together, and thus sustain the brackets I.

What we claim as new, and desire to secure by Letters Patent, is—

1. In a paper-dampening machine, the combination, with the frame to support the roll to be dampened, of a douche-pan, C, provided with an adjustable perforated water-pipe, o, and a board, G, extending transversely across the douche-pan and journaled at opposite ends in the adjacent sides of the same, and forming an adjustable deflector for spraying to any desired angle the water from the pipe o, and means, substantially as described, for rewinding the web to form a second roll, substantially as described.

2. In a paper-dampening machine, the combination, with the frame A to support the roll B, of means for rewinding the web after dampening the same and discharging the rewound roll, comprising pivotal brackets I, having guide-arms F F', carrying between them the journal ends of a spool, E, and brackets H, having fingers h h' and sockets h'', pivoted to the arms F, and catches g upon the arms F', substantially as and for the purpose set forth.

3. In a paper-dampening machine, the combination, with the frame A to support the roll

B, of means for rewinding the web after damping the same and discharging the rewound roll, comprising pivotal brackets I, having guide-arms F F', a drum, D, a spool, E, rotated by the drum and loosely supported in the guide-arms F F', to be moved therein by rewinding the web, and means, substantially

as described, for tilting the brackets I to discharge the spool E, substantially as set forth.

FREDERICK L. GOSS.

SAM G. GOSS.
